INVENTOR:

Frederick Medart.

by Robert Burns
ATTORNEY.

UNITED STATES PATENT OFFICE.

FREDERICK MEDART, OF ST. LOUIS, MISSOURI.

PARALLEL BARS FOR GYMNASIUMS.

SPECIFICATION forming part of Letters Patent No. 412,772, dated October 15, 1889.

Application filed July 19, 1888. Serial No. 280,422. (No model.)

To all whom it may concern:

Be it known that I, FREDERICK MEDART, a citizen of the United States, and a resident of the city of St. Louis, in the State of Missouri, have invented certain new and useful Improvements in Parallel Bars for Gymnasiums; and I do hereby declare the following to be a full, clear, and exact description of the same, reference being had to the accompanying drawings, forming a part of this specification, and in which—

Figure 1 is an end elevation, partly sectionized, of a set of parallel bars embodying my invention; Fig. 2, an enlarged end elevation of the lower end of one of the legs or posts, illustrating the means for adjusting the same on the supporting-base of the apparatus; Fig. 3, an enlarged detail side view of the same; Fig. 4, a detail view of bracket attachment; Fig. 5, an enlarged detail section illustrating the means for clamping the adjustable members of the legs or posts in position; Fig. 5^x, a detail side view of the same; Fig. 6, a detail section of the supporting-base of the apparatus, showing the caster appliance in its inoperative position; Fig. 7, a similar view of the same in its operative position, and Fig. 8 a detail plan of the same.

Similar letters of reference indicate like parts in the several views.

The present invention relates to certain improvements in the form of parallel bars for gymnasiums described in Letters Patent No. 187,477, issued February 20, 1877, to Philip Medart and Frederick Medart; and the present improvements have for their object to provide an improved construction of parallel bars in which are embodied the features of a parallel adjustment of the bars to and from each other in a horizontal plane, the holding of the parts at such adjustment in a strong and substantial manner, the ready and convenient adjustment of the parallel bars to any proper height, a guide or scale for indicating the various heights or adjustments in which the parallel bars can be placed, and an adjustable roller or caster attachment for affording means for the easy movement of the apparatus from place to place.

To enable others skilled in the art to which my invention appertains to make and use the same, I will now proceed to more fully de-

scribe the construction of parts and mode of using the same.

Referring to the drawings, A represents the 55 supporting-base, formed of two cast sections united together by longitudinal connecting-bars of wood, as in the Medart patent above referred to.

B B are a pair of side standards or uprights 60 projecting upward from each base-section to afford means for the pivotal attachment of the posts or legs C, that carry the pair of horizontal parallel bars D D, such pivotal attachment being effected by a pivot-bolt c, and a 65 clamping-bolt c', the slot c², through which the bolt passes in one of the parts, being made elongated, so as to admit of the pivotal adjustment of the posts or legs C upon the standards or uprights B. I have shown the pivot-bolt c arranged at the upper end of each standard and the clamping-bolt c' near the bottom of the same. The arrangement can, however, be reversed without departing from the spirit of my invention, and, similarly, the 70 elongated slot c² may be formed in either the upright B or the post C without affecting the spirit of my invention. The posts C are made in sections, the main or lower section C' being hollow, preferably of an open-sided U 75 shape, as shown, to receive the upper section C², which is of a round form preferably, and is arranged to slide vertically in the main section, C² being a guide-collar at the upper end of the section C' to hold the section C² in 80 place. The rod or section C² is clamped and held to the required adjustment by means of a clamping-sleeve E, encircling such rod or section and arranged to move laterally in a recess e in the section C', as shown, e' being a 85 laterally-projecting screw-threaded stem on the sleeve E, and E' a nut upon the same to effect the lateral adjustment of the sleeve E to clamp and bind the rod or section C² against the inner side of the main section C'. The 90 adjustable members or rods C² are made of wood or iron, as desired, and to their upper ends are secured the parallel bars D D by the following means:

F are T-shaped brackets, the vertical socket members F' of which fit upon the upper ends, rods, or members C², and are firmly secured thereto by vertical screw-bolts G, the heads of which are housed in the hollow swelled

- portions F^2 of the brackets. The horizontal members F^3 of the brackets are concaved on top to fit the under surface of the parallel bars D , and are secured thereto by bolts G' , 5 as shown. By this construction a firm and substantial connection is afforded between the parallel bars and their supporting feet or legs C without offering an obstruction to the ordinary use of such parallel bars.
10. H is a vertical series of holes in each of the main or lower leg-sections C , which I prefer to mark or number, so as to indicate the height of the parallel bars from the floor. In use a pin or rod h will be inserted in the 15 desired hole of the series, and the parallel bars then lowered until the end of the adjustable post member C^2 rests upon such pin or rod, after which they are firmly clamped in position by the nut R' and the laterally-moving clamping-sleeve E .
15. I are a pair of hollow counterpart projections extending out from the side of each base-section A , and forming preferably an integral part of the same. In the interior of 20 these projections the casters J are arranged, their vertical pivotal connections being formed by blocks I' , capable of limited vertical movement in the central orifices of the projections I , as shown, and having heads i 25 to prevent their slipping down through such orifices when the base of the apparatus is lifted from the floor. Ordinarily the casters will be entirely within the projections I , as indicated in Fig. 6, with the supporting-base 30 35 40 45 50
35. A resting directly on the floor. In order to bring the casters into use, it is only necessary to lift the base A up from the floor, when the casters will descend into the position indicated in Fig. 7, in which position they can be secured by the swinging latch-piece I^2 , pivoted at one end to the top of the projections I , its other end being engaged under a hook-lug i' , as indicated in Figs. 7 and 8. As so arranged the apparatus will be supported on the casters, and can be readily moved from place to place as desired.
- Having thus fully described my said invention,

what I claim as new, and desire to secure by Letters Patent, is—

1. A set of parallel bars for gymnasiums, 50 comprising, in combination, the base A and standards B , the bars D , and the supporting-posts C , secured to the standards B by a pivot-bolt c , so as to be capable of a pivotal adjustment in a lateral direction, essentially 55 as set forth.
2. A set of parallel bars for gymnasiums, comprising, in combination, the base A and the standards B , the posts C , provided with elongated slots, pivot-bolt c , and clamping-bolts c' , passing through said slots, essentially as set forth.
3. The combination, in a set of parallel bars for gymnasiums, of the posts or legs C , formed in sections, and made vertically adjustable one upon the other, the laterally-moving clamping-sleeve E , stem e' , and nut E' , substantially as described.
4. The combination, in a set of parallel bars for gymnasiums, of the parallel bars D 70 and posts C with the T -shaped bracket F , having a vertical socket member F' and a horizontal member F^3 , and having its top concaved, substantially as and for the purpose set forth.
5. The combination, in a set of parallel bars for gymnasiums, of the parallel bars D 75 and posts C with the T -shaped bracket F , having a vertical socket member F' , a hollow swelled portion F^2 , and a horizontal member F^3 , having its top concaved, and vertical attaching-bolt G , the head of which is arranged within the swelled portion F^2 of the bracket, substantially as described.
6. The combination of the hollow projections I , casters J , vertically-moving blocks I' , latch-piece I^2 , and hook-lug i' , substantially as set forth.
- In testimony whereof witness my hand this 12th day of July, 1888.
- FREDERICK MEDART.
- In presence of—
C. W. STEINMETZ,
E. W. BENSON, Jr.
